UNITED STATES PATENT OFFICE.

MURDICK LYTLE, OF DUKE CENTRE, PENNSYLVANIA.

METHOD OF OPERATING OIL-WELLS.

SPECIFICATION forming part of Letters Patent No. 406,362, dated July 2, 1889.

Application filed January 9, 1888. Serial No. 260,144. (No model.)

To all whom it may concern:

Be it known that I, MURDICK LYTLE, a citizen of the United States, residing at Duke Centre, in the county of McKean and State of Pennsylvania, have invented certain new and useful Improvements in the Method of Operating Oil-Wells; and I do hereby declare the following to be a full, clear, and exact description of the invention, such as will enable others skilled in the art to which it appertains to make and use the same.

My invention relates to a novel method of operating oil-wells which yield a small amount of oil, and which if operated in the ordinary manner and equipped as usual would not prove profitable.

My method consists in giving the piston or pistons of the pumping apparatus a very slow downward movement and a very quick and powerful upward movement, as will be hereinafter described.

My invention will be found quite important for use at feebly-flowing wells, inasmuch as without the same these wells if left idle, in a short time will become clogged with paraffine, sand, and the like, by the backing up of the undisturbed flow of oil, and thus they will gradually become inoperative and valueless. In order to prevent the entire loss of the investment in such wells it is desirable to continue pumping in such manner that the flow of oil, although feeble, shall be kept up by maintaining a certain height of the same in the pockets or bottom portions of the wells.

This can only be effected by a very slow pumping process regulated according to the ascertained flow of a well; but as such slow pumping with an ordinary plant—viz., a steam-boiler, steam-engine, or other motor, and attendants to each pump—would be expensive when the yield amounts to, say, from only one to four barrels of oil per day, it is necessary to adopt a method such as I have invented for doing the work, which, while it will be cheaper than other known methods, will avoid a slow upstroke of the pump-piston and its attendant disadvantages, especially when there is a slight leakage in the piston, or insure a quick and powerful upstroke and a very slow downstroke, thereby allowing time for the proper quantities of oil

to accumulate in the pockets or bottom portions of the wells before the respective strokes of the piston take place.

Before describing my invention I will state that in applying it I prefer to select a central location between a cluster of poor wells for the plant of a motor—say, a steam-boiler—from which steam is supplied to the several well-pumps around it, and each well-pump adapted to be operated in accordance with my method and moved by the steam-supply, so as to produce a number of strokes per hour or day in accordance with the yield of the well, such strokes being delivered at regular intervals and comprising a very quick upward movement and a very slow downward movement. By this means each oil-well can be pumped continually at a very slight expense, and the oil therein consequently kept at a proper pumping height, thus insuring a paying yield and a prolongation of the life of the well.

In the accompanying drawings, Figure 1 is a view of my invention, partly in elevation and partly in section. Fig. 2 is a modified construction of the same, and Fig. 3 is another modified construction of the same.

The letter A in the drawings, Fig. 1, represents a deep-well pump; B, a balancing walking-beam; C, a steam-cylinder; D, a steam-valve; and E, a valve-operating mechanism.

The pump A is an ordinary deep-well oil-pump, the piston-rod a of which is connected by means of a pin a' to the short arm b of the walking-beam B. The long arm b' of the said walking-beam is made quite bulky and heavy, and is provided with a weight b^2 , in order to overbalance the weight of the piston-rod, piston, and column of oil resting upon the latter. The walking-beam B is supported by means of a fulcrum-stand b^4 and fulcrum b^3 , and the weight b^2 at its lowest elevation rests upon a suitable abutment-cushion b^5 . At a suitable distance from the fulcrum b^3 the piston-rod c of the steam-cylinder C is pivoted by means of a pin c' to the walking-beam B. The piston c^2 is forced up by steam or other fluid under pressure, which is supplied through a pipe d , leading from a reservoir centrally located in a cluster of wells. The valve D, by means of which the operating fluid is ad-

mitted to and exhausted from the cylinder, consists of an ordinary four-way cock d' , communicating with a supply-pipe d , exhaust-pipe d^2 , pipe d^3 , leading to the cylinder C, and safety-valve d^4 . An arm d^5 is attached to the cock d' , which, by means of a pin d^6 , is connected to a rod e of the valve-operating mechanism E. The rod e is provided with a slot e' , in which the pin d^6 is confined, and whereby only an end portion of either the forward or back stroke of the rod e is transferred to the pin d^6 . The rod e is pivoted by means of a pin e^2 to the lower arm e^3 of a lever e^4 , suitably hung at e^5 to the stands e^6 , the upper e^7 of which lever is provided with a weight e^8 . The arm e^3 is provided with a heel e^9 , which, by coming in contact alternately with two end abutments $e^{10} e^{11}$, limits the oscillations of the lever e^4 . A crank-arm e^{12} is formed with the lever e^4 , the pin end e^{13} of which arm is confined in a slot b^7 in a connecting-rod b^8 . The connecting-rod b^8 is, by means of a pin b^9 , connected to the walking-beam B, and thus the end portions only of the strokes of the rod b^8 are utilized for moving the lever e^4 .

When the arm d^5 stands as represented by full lines in the drawings, the steam or other motor fluid enters the cylinder C, and moves the piston c^2 up until it occupies a position shown by dotted lines, whereby the weighted part of the walking-beam B is also elevated, as shown by dotted lines. By this movement the piston-rod is moved down to its lowest elevation, as indicated by dotted lines. The rod b^8 , rising with weighted part b' , pulls up the crank-arm e^{12} , and moves the lever e^4 sufficiently beyond its upright position as to enable the weight e^8 to throw it into its other extreme position, as the dotted lines show, in which position it is held by the abutment e^{11} . By the said movement of the lever e^4 the arm d^5 is suddenly turned to its reversed position, and the four-way cock d' allows the steam to blow out of the cylinder C through pipe d^2 into the atmosphere. By means of the slots b^7 and e' the motion of the lever e^4 begins, while the upward motion of the weighted lever-arm b' is nearing its termination, and the motion of the lever e^4 is accelerated toward its termination independently of the motion of the walking-beam B, and while at its highest speed said lever e^4 reverses the position of the four-way cock d' , and thus the piston c^2 is always raised to its proper elevation. The steam in the pipe d , after being cut off from the cylinder C, is caused to communicate with the safety-valve d^4 , which breaks the force of the inertia and prevents the pipe from being bursted. As soon as the steam is allowed to blow out from the cylinder C, the arm b' by means of its weight (exceeding the weight of the piston-rod and the oil supported by the pump-piston) will descend with a quick motion, thereby raising the piston-rod and the oil in the pump. As soon as the descending weight b^2 touches the abutment-cushion b^5 , the down-

ward motion of the walking-beam B ceases, the weight of the arm b' alone not being sufficient to raise the piston-rod and piston. At the last stage of its descent the connecting-rod b^8 reverses the position of the lever e^4 , as described, and thus causes the four-way cock d' to be reversed, whereupon the steam is again admitted to the cylinder C and the above-described operation is repeated. The arm b' may be made sufficiently heavy to effect the upstroke of the piston without the weight b^2 , and in that case an abutting-column will be provided by which the descent of the arm b' is limited.

Instead of conducting the steam or other motor fluid from a boiler or reservoir to the different pumps, the steam or motor fluid may be employed near the boiler for driving an engine, and this engine may be made to operate the well-pumps around it by means of reciprocating wires, each pump being provided with a suitable lifting mechanism connected to said wires, as will now be described.

In the drawings, Fig. 2, a means is shown for lifting the weight by a crank-arm on a shaft, and in Fig. 3 a means for lifting the weight by a chain-and-pulley rack and pinion.

The walking-beam B in Fig. 2 has an arm b' heavy enough to overbalance and raise the piston-rod a of the pump A by means of the arm b . The arm b' is connected by means of a connecting-rod c^3 , pin c' , and wrist-pin f to a crank f' on a shaft F, which latter is suitably hung in a pedestal f^2 , and carries a disk G and a loose-fitting gear-wheel H. The disk is at two opposite points provided with ratchet-teeth into which a spring-pawl g' of the wheel H gears. The wheel H gears into a pinion h' on a shaft F' , suitably hung to the pedestal h , and to said shaft a wheel H' is attached, which gears into a pinion h^2 on a shaft F^2 , suitably hung to the pedestal b^4 of the walking-beam B. This shaft F^2 is provided with a wheel H^2 , made fast to it, and two loosely-fitting lever-arms I I', having spring-pawls $i^1 i^2$, and being suspended on cords $i^3 i^4$, which run over a guide-pulley i^5 , and are connected with one of the above-mentioned reciprocating wires i^6 . The arm I is provided with a weight i , by which the pawl i^1 is enabled to operate the wheel H^2 while the said arm descends, and the arm I', with the pawl i^2 , operates the wheel H^2 while being pulled up by the wire i^6 . By this construction the wheel H^2 is propelled at each movement of the wire i^6 , and this motion of the wheel H^2 is communicated in the manner shown to the wheel H on the shaft F. The pawl g' of said wheel revolves and glides over the plain surfaces of the disk G until it comes in contact with the ratchet-teeth g thereon, when it communicates its motion to the disk, and thus causes the crank f' to be slowly elevated from its lowest to its highest elevation, together with the weighted arm b' . This movement causes the piston-rod a to slowly

descend in the pump A. As the disk G is thus moved up and over the point of dead-leverage of the crank, the weight of the arm b' causes the same to move ahead of the pawl 5 g' with a quick speed till the crank f' arrives at its lowest elevation, thus finishing the up-stroke of the pump with the proper speed and an invariable elevation. The arrangement of the ratchet-teeth g is such that allowance is 10 made for different points near that of the lower dead-leverage, at which the crank f' may occasionally stop in its descent, and thus, after each downstroke of the crank, the pawl will, without perceptible loss of time, engage 15 with one or the other of the said ratchet-teeth and immediately begin to move up the crank again in the manner aforesaid. It is easily seen that by employing more or less of intermediate gear-wheels the time for raising the 20 weighted arm b' may be lengthened or shortened, according to the judgment of the attendant of a well-district under his supervision.

The described pawl and wheel mechanism 25 may be employed to revolve a shaft g^2 , Fig. 3, with a geared pinion G' , having a blank portion g^3 on its toothed periphery, and a toothed rack J , having guides jj , suitably fastened to a pedestal b^4 , which latter supports a grooved pulley b^{10} , chain b^u , and weight b^2 . The chain b^{11} is fastened to the upper end of the rack J , and the rack is fastened to the upper end of the piston-rod a . The pinion G' while slowly revolving moves the rack J and piston-rod a 30 down until its teeth have all passed through the rack-teeth and the blank portion g^3 has arrived in front of the rack, when the rack and piston-rod are lifted by the liberated weight b^2 , and the upstroke of the pump is 35 effected. Said upstroke may be regulated by means of a spring a^2 interposed between the pump and rack with the good effect of giving more energy to the beginning portion of the upstroke of the piston-rod, and thus insuring 40 the quick and positive closing of its valve.

In shallow wells the weight of the piston-rod and oil-column is considerably reduced, and the operation of the pump requires very little power, so that the spring a^2 alone, with- 45 out the aid of a drop-weight, may be employed to effect a quick upstroke for the purpose of pumping on the principle above described.

The above-described pawl-and-wheel mechanism, Figs. 2 and 3, may be modified to suit 50 the convenience of power transmission, as it would in certain instances be more advantageous to use a belt h^4 or chain and pulley H^3 instead of reciprocating wires and pawls; and in wells with a very changeable flow of 55 oil it may be advisable to use both methods of transmitting power from a centrally-located motor to such pumps in order to adjust the number of pump-strokes per hour or day to the changing issue of the wells without in- 60 jurious loss of time. In such case the shaft F^3 , to which the pulley H^3 and a pinion h^3 are fastened, is supported by an ordinary mov-

able bearing, by means of which it can be moved away, as shown, from the wheel H^2 , or can be moved toward it until the pinion h^3 70 gears into the wheel H^2 , whereby the quicker motion of the pump is established.

It is easily seen that with my invention a number of oil-pumps can be operated from a centrally-located motor with a quick up-stroke and a suitable number of strokes per hour or per day, and that the number of such strokes in each pump can be changed to more or less without disturbing the operation of the other pumps and without undue loss 80 of time. By using my invention the entire yield of the wells is secured, the capital invested in the boring and equipping of the wells does not become a dead loss, the pumps used for elevating the oil while boring need 85 not be exchanged for smaller pumps, and one man can attend to all the pumps while another man attends to the central motor. The ordinary pumps used for testing wells under the operation of boring have a diameter of two inches, and if a pump of one-inch diameter, which would be equal to the small yield, would, with the ordinary means of operation, be capable of elevating such yield it would have to make four strokes 95 while the said ordinary two-inch pump makes but one, and consequently the packing of the small pump would have to be renewed four times instead of once as with the large pump. This renewal of packing necessitates extra 100 labor and time, and is a very expensive operation, and sometimes interferes with the steady flow of the oil-well; hence it will be seen that the use of a two-inch pump is the most advantageous. 105

With my invention an invariable quick up-stroke of the oil-pump is secured, while the downstroke is slow and variable, and this is accomplished without substituting a different pump for the one used in the boring operation, which pump is, as above stated, of, say, two-inch diameter.

It will be apparent from the foregoing description that the slow downward movement of the piston is against the resistance of the 115 weighted lever or spring, and thus while the speed of the piston is rendered very slow a power for raising the piston and its load of oil is accumulated. Thus a twofold purpose is accomplished—viz., time allowed for the 120 oil to flow into the bottom of the well between the respective strokes of the piston, and a power is stored for the powerful and quick elevation of the piston.

What I claim as my invention is—

The within-described method of operating slowly-flowing oil-wells equipped with lifting-pumps, as described, consisting, first, in automatically lowering the pump-piston very slowly relative to its upward movement, 130 thereby allowing time for a full supply of oil to flow into the well by the time the piston has completed its downstroke; second, in such movement accumulating a powerful

force for raising the piston, and, third, automatically withdrawing the lowering force and allowing the said accumulated raising force to automatically come into action and suddenly, powerfully, and automatically raise the piston and the oil carried by the same, substantially as described.

In testimony whereof I affix my signature in presence of two witnesses.

MURDICK LYCLE.
